UNITED STATES PATENT OFFICE.

FELICISSIMO C. SILVA, OF LOWELL, MASSACHUSETTS.

PUZZLE.

1,111,923.

Specification of Letters Patent. Patented Sept. 29, 1914.

Application filed May 8, 1914. Serial No. 837,215.

To all whom it may concern:

Be it known that I, FELICISSIMO C. SILVA, a citizen of the United States, residing at Lowell, in the county of Middlesex and State 5 of Massachusetts, have invented certain new and useful Improvements in Puzzles, of which the following is a specification, reference being had to the accompanying drawings.

10 This invention relates to new and useful improvements in puzzles and more particularly to what is known as an interlocking block puzzle, the main object of the present invention residing in the provision of an exceedingly perplexing and intricate puzzle of 15 the above character which will provide a severe test for the ingenuity of one attempting to solve the same and consists of a plurality of bars formed with co-engaging recesses, whereby the several bars can be readily interlocked.

Another object of the present invention is the provision of a puzzle of the above character which will possess advantages in points 25 of efficiency and durability, is inexpensive to manufacture and, at the same time, is simple in construction and operation.

With the above and other objects in view, the invention consists in the novel features 30 of construction, combination and arrangement of parts as will be hereinafter referred to and more particularly pointed out in the specification and claims.

In the accompanying drawings forming a 35 part of this application, Figure 1 is a detail perspective view illustrating the first step taken in the assembling of my improved puzzle. Fig. 2 is an elevation illustrating the second step. Fig. 3 is a similar view 40 illustrating the third step. Fig. 4 is a similar view illustrating the bars in their interlocked position. Fig. 5 is an elevation illustrating one of the bars which is included in one of the sets; and Fig. 6 is a side elevation 45 of one of the bars included in the other set.

In carrying out my invention, I provide two sets of bars each set composed of four bars, one of the forms of which is illustrated in Fig. 5, while the other form is illustrated 50 in Fig. 6. One set of bars includes a longitudinal body 1 provided adjacent each end and at the central portion with recesses 2, which extend inwardly from each of the longitudinal edges of the body in opposed relation to form a connecting neck 3. The bars including the other set comprise an

elongated body member 4 having a central opening 5 and are further provided with a recess 6 extending inwardly from one of the longitudinal side walls of the opening 5, the purpose of which will be hereinafter more fully set forth.

It is the object of my improved puzzle to interlock the bars 1 with the bars 4, whereby to provide a severe test for the ingenuity of one in attempting to unlock the bars and separate them and also for assembling them. The first step in the assemblage of my improved puzzle, is indicated in Fig. 1. In order to arrange the bar 1 in the position 65 illustrated in Fig. 1, the bars 4 are first arranged in spaced parallel relation and the bar 1 inserted through the openings 5 and the recesses 2 being disposed in alinement with the side walls of the opening, so that 70 the bar 1 may be readily turned up to the position illustrated in Fig. 1. The bar 7 is then inserted within the openings 5 and the connecting neck portions 3 thereof are arranged within the recesses 6, so that the upper 75 face of the bar will lie flush with the lower wall of the openings 5. The bars 8 and 9 are then arranged in position upon the bar 7 and the three are then turned at right angles, the manner of turning being illustrated in Fig. 3, until they are disposed in an upright position, as illustrated in Fig. 4. It will be apparent that it will take considerable skill to remove the bars from the 80 openings 5 from their position illustrated in 85 Fig. 4.

In order to remove the bars from the openings 5, the bars 7, 8 and 9 are moved together and thence turned to the position 90 illustrated in Fig. 3, whereby further turning movement will dispose them in the position illustrated in Fig. 2, whereby they may 95 be readily removed from the openings 5, one at a time. It will be noted that the bar 1 is somewhat wider than the bars 7, 8 and 9, so as to render the puzzle more difficult to 100 operate in view of the fact that should the person operating the same attempt to turn the bar 1, it will be readily seen that it will be impossible to remove this bar in connection with the others, in view of the width of 105 the same.

From the above description taken in connection with the accompanying drawings it will be apparent that I have provided a 110 simple and durable puzzle which consists of a plurality of interlocking bars so con-

structed as to form an exceedingly perplexing puzzle and which will provide a severe test for the ingenuity of one attempting to lock the bars together or remove the same from their locked position. It will also be apparent that the device can be manufactured and placed upon the market at a comparatively low cost. It is to be understood that these bars may be made of any suitable material and any size whatsoever.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

Having thus described this invention, what I claim is:

1. A device of the class described including a plurality of interlocking bars formed in sets, each of the bars of one set including an elongated body having spaced recesses formed inwardly from each of the longitudinal edges of the body, the bars of the other set including an elongated body having a centrally arranged elongated opening to receive the bars of the other set and

further provided with a recess formed in one of the walls of said opening, whereby to receive the material between the recesses of the other bars and one of the first sets of bars being substantially wider than the remaining bars of that set, as and for the purpose set forth. 35

2. A device of the class described including a plurality of interlocking bars formed in sets, the bars of one set including an elongated body having spaced recesses extending inwardly from each of the longitudinal edges of the body, the bars of the other set including an elongated body having a centrally arranged elongated opening of a length sufficient to receive one of the bars of the first set in a vertical position and the remaining bars in a horizontal position, said bars being further provided with a recess communicating with one of the side walls of the opening adapted to receive the material between the recesses in the first bars, as and for the purpose set forth. 45

In testimony whereof I hereunto affix my signature in the presence of two witnesses. 50

FELICISSIMO C. SILVA. 55
